VENDING MACHINE

Samuel M. Campbell, Rock Island, Ill.

Application December 31, 1931
Serial No. 582,343

4 Claims. (Cl. 194—58)

My invention relates to improvements in vending machines.

The objects of my invention are to provide an efficient, coin operated vending machine for small packages, of superior simplicity which can be operated without utilizing springs.

I attain these objects by the means illustrated in the accompanying drawings, in which,—

Figure 1 is a plan view of my apparatus;

10 Figure 2 is a front elevation foreshortened;

Figure 3 is a cross-sectional detail on the line 3—3 of Figure 6;

Figure 4 is a longitudinal sectional detail on the line 4—4 of Figure 6;

15 Figure 5 is a plan view showing an alternate form of slide;

Figure 6 is a bottom view with the bottom plate removed and showing a part of the top plate of the base broken away.

20 Similar numerals refer to similar parts throughout the several views.

My apparatus comprises a hollow base, 1, which may be of any desired form, having a bottom plate, 2, secured thereto by suitable locking means.

25 The base is provided with a top plate, 3, which may be united to the base by set screws, 3a, or may be cast integral therewith.

In the drawings I have shown the bottom plate provided with a shoulder, 2b, which fits into a 30 groove, formed in the lower portion of the housing and thus secures one end of the bottom plate in place.

A lock, 2a, is united to the other end of the bottom plate, and the bolt of the lock is adapted 35 to engage a slot or groove, 1a, formed in the opposite end of the housing to lock the bottom plate in position. The lock may be operated by a key in the ordinary way or by such other means as may be desired, and various methods of securing the bottom plate may be provided or 40 other equivalent forms may be utilized for providing an opening into the coin reservoir which is formed by the interior of the base housing, 1.

Upon the top plate of the base housing I 45 secure a slide housing, 5, for the delivery slide. This slide housing may be formed integral with the top plate of the base or may be secured thereto by set screws, 5a, or other suitable means.

Upon the slide housing I mount the package 50 container or body, 6, which may be secured to the slide housing by the set screw, 6a, or other suitable means. The interior of the body may be so shaped as to conform to the various kinds of packages which it is desired to vend. In the 55 drawings I have shown two cylindrical bores, 10,

extending vertically of the body, 6, which are adapted to contain small round tin cans or other flat, round receptacles for tablets such as aspirin, bicarbonate of soda, etc., which it may be desirable to vend in small packages, and I have 60 shown the delivery slide, 14, provided with two circular seats, 15 and 15a, each of which is adapted to receive and deliver one of the small round cans.

The delivery slide comprises a rectangular bar, 65 14, provided with horns, 14a, at the ends thereof to assist in manipulating it manually. The seats, 15 and 15a, are cut in the bar as described and the intermediate portion of the bar forms a seat upon which the cans in either bore may 70 rest when said portion is in alignment therewith, it being intended to deliver the merchandise from this machine from opposite ends of the slide, 14.

Notches, 20, are cut in the lower face of the 75 bar, 14. A locking lever, 23, is mounted upon a pivot, 21, secured in bosses, 25, extending downwardly from and formed integral with the top plate, 3, of the base, 1.

The forward end of the lever, 23, has an upwardly projecting dog, 19, formed integral therewith which is adapted to enter either one of the notches, 20, and lock the slide. The rear end of the lever, 23, has an upwardly projecting lug, 22, formed thereon which may contact with the 85 top plate of the base housing to limit the throw of the lever, 23. The rear end of the lever, 23, is also provided with a weight, 24. The front end of the lever, 23, is also provided with a fork or a pair of short fingers, 18, turned upwardly 90 and spaced apart the desired distance.

My machine is intended principally to be manufactured for use in vending articles which sell for five cents and when so made, the fingers, 18, will be spaced far enough apart so that they 95 would permit a penny or any coin smaller than a nickel to pass through between them and drop into the reservoir without actuating the lever, 23.

These fingers are positioned directly below the lower end of a coin slot, 12, which is united to the 100 front of the body by a set screw, 12a, or other suitable means and which is provided with a coin opening, 13, in which the coins may be inserted. When a coin of the right size is inserted in the machine, it will drop down the slide until it rests upon the upper ends of the fingers, 18. The lever, 23, is so balanced that the rear end thereof will normally be carried downwardly and the dog, 19, will seat in one of the notches, 20, and lock the 105 slide against movement.

When a coin of the correct denomination is placed in the machine, the coin as it rests upon the fingers, 18, will be of sufficient height to bear upwardly against the top of the housing, 15, and 5 downwardly against the fingers, 18, as the slide, 14, carries the coin to one side and the coin will then force the front end of the lever, 23, downwardly, thereby disengaging the lug, 19, from the notch, 20, and permitting the slide to be pushed 10 in one direction or the other as the case may be, thus carrying one of the packages to be vended, beyond the slide housing where it can be picked up by the purchaser from the seat, 15 or 15a. In order to permit the slide to move sufficiently to 15 cause the coin to depress the unweighted end of the lever, 23, the notches, 20, are elongated as shown in Figure 5.

The slide, 14, has its front face provided with two slots, 17 and 17a, and the portion, 14b, of the 20 slide intermediate the slots, 17 and 17a, being in line with the coin as it rests upon the fingers, 18, will carry the coin to one side or the other of the center. An extended slot, 17c, is formed in the 25 top plate, 3, which registers with the slot in the coin slide, 12, and extends a sufficient distance beyond the fingers, 18, in either direction so that the coins when carried by the intermediate portion, 15b, beyond the fingers, 18, can drop downwardly into the reservoir formed by the base.

30 The body, 6, has suitably secured to the top thereof, a top plate, 7, with a cover plate, 8, hinged thereto at a hinge, 9. The top plate, 7, has a hasp, 7a, extending upwardly through a suitable slot in the cover plate, 8, and may be locked by a padlock, 11.

A bracket, 16, is united to the top plate, 7, by which the apparatus may be bolted to a suitable support so as to secure same in upright position.

In the operation of my device, the slide is 40 pushed to either side. The package reservoirs are then loaded, and in loading them one of the boxes will drop into the seat in the delivery slide which happens to be in alinement with one of the bores.

45 The machine being secured in upright position with the slide, 14, at its limit of travel in one direction, a coin of the required denomination is dropped into the coin slide, 12, and lights upon the fingers, 18, the weight, 24, upon the weighted 50 end of the lever being sufficient to counterbalance the weight of the coin and retain the lever, 23, in locked position. As the slide, 14, is pushed manually in the opposite direction, the coin bears upwardly against the top of the housing, 5, and 55 downwardly against the arms, 18, of the lever, 23, thus forcing the front end of the lever, 23, down and releasing the detent, 19, from the notch, 20. As the slide, 14, is then pushed manually transversely of the machine the charged seat 60 carries the can therein out where it may be reached by the purchaser. At the same time, the other seat is carried under its respective bore and one of the cans drops into it from that bore. As the slide, 14, is pushed out for the delivery of 65 the can contained therein, the intermediate portion, 14b, carries the coin along with the slide and as the coin is removed from the fingers, 18, the weight, 24, pulls the rear end of the lever, 23, downwardly and the lug, 19, then engages the notch, 20, which is nearest the seat just brought 70 into charging position. Another coin may be then inserted and the operation repeated as long as the cans remain in the bores.

75 Inspection openings, 26, are formed in the front and rear plates of the body, 6, which permit an

intending purchaser to look into the package reservoir and ascertain whether there are any packages therein before dropping in his nickel.

While this machine has been primarily designed for use with nickel packages, it is obvious 80 that the same construction may be used for quarters or pennies or other coins.

In Figure 5 I have shown an alternate form 85 of seat, 15b and 15c, for the packages which can be used in case square packages are to be vended instead of round ones.

I claim:

1. A vending machine comprising a hollow base, a housing mounted upon the base, a body having a plurality of vertical bores formed therein mounted upon the housing, a slide seated in the housing and slidable therein, seats formed in the slide corresponding to the bores and adapted to be respectively aligned in alternation with their corresponding bores, a pair of notches formed in the lower face of the slide, a coin tube united to the body, a lever pivoted in the base having a detent at one end adapted to enter either of the notches in the slide, and a weight at the opposite end, such lever being tiltable in one direction by downward pressure of the coin resting on one end thereof when moved to one side of the middle and in the opposite direction by the weight secured to the opposite end thereof when freed of the coin and means adapted to 100 cause the coin to exert a downward pressure upon the unweighted end of the lever as the slide is moved along its seat in the housing.

2. A vending machine comprising a hollow base, a housing mounted upon the base, a body having a 110 plurality of vertical bores formed therein mounted upon the housing, a slide seated in the housing and slidable therein, seats formed in the slide corresponding to the bores and adapted to be respectively aligned in alternation with their corresponding bores, a pair of notches formed in the lower face of the slide, a coin tube united to the body, a lever pivoted in the base having a detent at one end adapted to enter either of the notches in the slide, a weight at the opposite end, such 120 lever being tiltable in one direction by the pressure of the coin against the top of the housing and the lever when resting on one end thereof when carried by the slide to either side of the center and in the opposite direction by the weight 125 secured to the opposite end thereof when freed of the coin, and means united to the slide to remove a coin from the lever when the slide is moved through the limit of its travel.

3. In a vending machine the combination with 130 a hollow base, of a housing mounted upon the base, a body having a plurality of vertical bores formed therein mounted upon the housing, a slide seated in the housing and slidable therein, seats formed in the slide corresponding to the 135 bores and adapted to be respectively aligned in alternation with their corresponding bores, a pair of elongated notches formed in the lower face of the slide, a coin tube united to the body, a lever pivoted in the base having a detent at one end adapted to enter either of the notches in the slide, a weight at the opposite end, such lever being tiltable in one direction by the downward pressure of the coin on one end thereof and in the opposite direction by the weight 140 secured to the opposite end thereof when freed of the coin, and means including the conjoint action of the top of the housing and the slide adapted to cause the coin to exert a downward pressure upon the unweighted end of the lever 145 150

as the slide is moved along its seat in the housing. 4. A vending machine comprising a hollow base, a housing mounted upon the base, a body having a plurality of vertical bores formed there-in mounted upon the housing, a slide seated in the housing and slidable therein, seats formed in the slide corresponding to the bores and adapted to be respectively aligned in alternation with their corresponding bores, a pair of notches formed in the lower face of the slide, a coin tube united to the body, a lever pivoted in the base having a detent at one end adapted to enter either of the notches in the slide, a weight at the opposite end, such lever being tilttable
